(57) **CLAIM**

The ornamental design for a truck grille, as shown and
described.

DESCRIPTION

FIG. 1 is a front perspective view of the truck grille of the
present invention as the same could be mounted within a
truck;

FIG. 2 is a top plan view of the truck grille of the present
invention;

FIG. 3 is a front elevation view of the truck grille of the
present invention, which is substantially similar to its rear
elevation view;

FIG. 4 is a side elevation view of the front truck grille of the
present invention; and,

FIG. 5 is a bottom plan view of the truck grille of the present
invention.

The broken line drawings in FIG. 1 are for illustrative pur-
poses only and form no part of the claimed design.
